UNITED STATES PATENT OFFICE.

GEORGE J. CARTER, OF BROMBOROUGH, AND LAUCHLAN GRANT McFARLANE, OF LIVERPOOL, ENGLAND.

INTERNAL-COMBUSTION ENGINE.

Application filed October 22, 1918. Serial No. 259,251.

To all whom it may concern:

Be it known that we, GEORGE JOHN CARTER, a subject of the King of Great Britain, residing in Bromborough, in the county of 5 Chester, England, and LAUCHLAN GRANT McFARLANE, a subject of the King of Great Britain, residing in Liverpool, in the county of Lancaster, England, have invented certain new and useful Improvements in Internal-Combustion Engines, of which the 10 following is a specification.

This invention relates to internal combustion engines of that class in which each unit comprises a pair of open-ended cylinders 15 each provided with two oppositely moving pistons, the upper piston of the one cylinder and the lower piston of the other being in each case respectively connected by crossed rods through a cross-head and connecting rod to the one crank of a pair of cranks; and the invention has reference particularly to the design of open type vertical marine engines of this class specially suitable for the mercantile service. In such engines the cross-heads may be partly or 20 wholly enclosed by light portable plates which can be removed whilst the engine is running so as to afford easy access to the working parts, and the object of the invention is to provide such an engine of cheap 25 and simple construction adapted to facilitate manufacture and erection and in which, as in the case of marine steam engines, access may be readily obtained to the working parts for inspection, adjustment and repair.

According to the present invention the 30 centre lines of pairs of cylinders comprising a unit are spaced as closely together as possible, so that the two cranks which are approximately 180° apart may be separated only by the width of the intervening crank web, so that the crossed rods connecting the 35 respective upper pistons to the cross-heads in relation to which they are laterally displaced may have a minimum of obliquity; each pair of cylinders is carried on two pairs of columns the insides of which form the main guides for the cross-heads, and as the 40 centre lines of the pairs of columns and the cylinders coincide, the lateral space between the adjacent columns is comparatively short. Instead therefore of utilizing this space, as is usual in this class of engine, for the guides 45 which take the side thrusts due to the hori-

zontal components of the forces transmitted by the oblique rods; these guides are formed on the fore-and-aft oppositely disposed sides of the pairs of frames; the pair of main cross-heads having, on their corresponding remote sides, extensions which form slipper-blocks for these guides. This construction permits of the upper ends of the main connecting rods being of forked configuration and yet provides sufficient space between the adjacent columns to permit free access to and inspection of the inner bearings of the forked ends and the cross-head pins, this construction is also found to possess considerable advantages in the manufacture and erection of the engine.

The invention is illustrated in the accompanying drawings, which show a unit section of a marine engine comprising pairs of cylinders, oblique crossed rods, cross-heads, 75 main connecting rods, cranks, columns and guides.

Fig. 1 is a side elevation, one of the cylinders being shown partly in medial section, and the cross-heads being shown partly in 80 section on the line I, I, of Fig. 3.

Fig. 2 is an end elevation.

Fig. 3 is a corresponding plan, to a larger scale in section on the line III, III, of Fig. 1, and

Fig. 4 is a fragmentary plan view of a modification.

The directions in which the sections are viewed are indicated by the arrows placed adjacent to the line denoting the plane of 90 the section.

A is the main cylinder casting which forms the outer water jacket and which carries the cylinder liners a^1 ; this casting is made integral with or is bolted to an entablature a^2 which is carried by the two pairs of columns B.

The lower pistons C are connected directly to the respective main cross-heads D, which are in alignment with them, by the 100 rods E and the upper pistons C' are connected by the rods E' to the upper cross-heads F which in turn are connected by pairs of crossed rods G, G, and G' G', to the respective cross-heads D. The cross-heads F 105 may each be fitted with a piston f^1 of rectangular configuration fitting a chamber H of corresponding section which is adapted to form the air supply pump; the chambers H are located on opposite sides of the upper 110

cross-head guide b^1 which takes the lateral thrusts due to the tensile stresses normally transmitted by the crossed rods, and the sides b^2 of the chambers form auxiliary guides to take the thrusts should the crossed rods be for any reason subjected to compression.

a^3 are clearance gaps for the rods G, G', G'', G'''.

The main cross-heads D are connected to 10 their respective cranks J by connecting rods K having forked ends k^1 pivoted on cross-head pins d^4 carried by the cross-heads. The crank shaft is carried in main bearings m^1 formed on the lower frame M which forms 15 the engine bed-plate by which the bottoms of the columns B are carried.

The cross-heads D (see Fig. 3) are fitted with slipper plates d^2 which are secured by studs or bolts d^3 and may be lined with white 20 metal d^4 , and these slide on the guide-plates b^1 secured to the inside faces of the columns B by the studs b^2 which plates take the thrust of the main connecting rods.

Extensions d^5 are formed on the outer 25 sides of the cross-heads D these may be rigidly connected to the cross-head body by the box-like frame d^6 and webs d^7 ; these extensions d^5 which form slipper plates may be lined with white metal d^8 and they slide on 30 the guide plates b^3 secured to the side faces of the columns B by the studs b^4 . The slipper plates d^5 and guide plates b^3 take the horizontal components of the oblique forces 35 transmitted by the crossed rods G, G' when the latter are, as in normal working in tension.

In order to take the oppositely acting horizontal components of the oblique forces transmitted by the crossed rods should the 40 latter be in compression auxiliary guide plates b^5 secured by studs b^6 to the columns B may be provided to guide the outer surfaces of the slipper plates d^5 which surfaces may be lined with white metal d^9 .

45 In the modification shown in Fig. 4 the slipper plates d^5 are, instead of being made integral with the cross-head D, detachably secured to the latter by the studs d^{10} , a construction which permits the guide surfaces 50 being examined and adjusted without removal of the cross-head.

As stated the arrangement of the guides b^3 and b^5 on the outsides of the columns B leaves the space between the columns unobstructed and permits free access to both sides 55 of the forked ends of the connecting rods.

In a similar construction the white metal linings may be dispensed with, the slipper plates being made of a suitable metal

adapted to work on the guide plates; and in some cases the latter may be omitted, the faces and sides of the columns being provided with surfaces which may be machined to form guides.

An engine would usually comprise several 65 of the unit sections described, according to the power required, and these would be tied together to form a single braced structure; and the general arrangement and the details described are well adapted for the repetition 70 manufacture of standard parts.

The details of construction in regard to the exhaust ports a^4 and the fuel ports a^5 and the valves controlling them; the trunk 75 pistons c^1 and the mode of attachment of the rods E and E' to the pistons may be of any usual and suitable construction. The working parts such as the cross-heads D and connecting rods K may be enclosed by detachable enclosure plates bolted to the main 80 structure.

Having now particularly described and ascertained the nature of our said invention, and in what manner the same is to be performed, we declare that what we claim is:— 85

1. In an engine of the class described, a pair of cross heads arranged side by side, operating means therefor, slipper plates extending from the outer sides of the cross heads, and two pair of columns between 90 which the cross heads slide, the columns of each pair having outer guide surfaces for said slipper plates, the inner sides of each pair of columns being spaced far enough apart to permit access to be had to the cross 95 heads and their operating means.

2. In an engine of the class described, a pair of cross heads D arranged side by side and spaced apart, two pair of columns B between 100 which the cross heads slide, slipper plates d^5 extending from the cross heads each pair of columns having on their outer sides guide means b^2, b^5 for the slipper plates, the inner sides of each pair of columns being spaced far enough apart to permit access to the cross heads and their operating means, and operating means for the cross heads applying power thereto at an angle to the line of movement of the cross heads and transverse to the guide means and slipper 110 plates, substantially as described.

In witness whereof we have set our hands in presence of two witnesses.

GEO. J. CARTER.

LAUCHLAN GRANT McFARLANE.
